George B. Greenwood, 3652 Brookgrove,
Grove City, Ohio

Filed Feb. 13, 1964, Ser. No. 78,627

Term of patent 3½ years

(Cl. D33—3)

FIGURE 6 is a rear elevational view of the book end. The dominant features of my new design reside in those portions shown in full lines on the drawing.

I claim:

The ornamental design for a book end, as shown and described.
